United States Patent Office

Des. 186,427
Patented Oct. 27, 1959

186,427

SLIPPER OR SIMILAR ARTICLE

Louis H. Carlin, New York, N.Y.

Application June 11, 1958, Serial No. 51,298

Term of patent 3½ years

(Cl. D7—7)

Fig. 1

Fig. 2

Fig. 1 is a front perspective view of a slipper or similar article showing my new design.

Fig. 2 is the opposite side with the cuff portion in upward position.

The dominant features of my design reside in those portions shown in full lines on the drawing.

I claim:

The ornamental design for a slipper or similar article, substantially as shown and described.
